UNITED STATES PATENT OFFICE.

JOHN POTURNAJ, OF SILVER SPRINGS, NEW YORK, ASSIGNOR OF ONE-HALF TO
FRANCIS J. HANLEY, OF SILVER SPRINGS, NEW YORK.

COMBINATION PADLOCK.

Application filed July 19, 1928. Serial No. 293,921.

This invention relates to certain new and useful improvements in combination padlocks and has for its primary object to provide a padlock in which one long leg of the shackle 5 extending into the lock casing is engaged and retained therein by a locking pin controlled in its sliding movement by rotatable disk tumblers operated by the provision of a pair of manually shiftable handles extending 10 through slotted openings in the lock casing.

A further object of the invention is to provide a combination padlock of the above type in which there is provided a plurality of 15 disk tumblers having angle lugs projecting from the peripheral edge thereof with a handle carried by two other disk tumblers to effect rotation thereof and also rotation of the other tumblers for disposing all of said tumblers in positions to permit sliding movement of the shackle engaging pin for disengagement from the shackle to permit opening of the lock.

With the above and other objects in view 25 that will become apparent as the nature of the invention is better understood, the same consists in the novel form, combination and arrangement of parts hereinafter more fully described, shown in the accompanying drawings and claimed.

Figure 1 is a side elevational view of the combination padlock constructed in accordance with the present invention, showing two operating handles for disk tumblers within 30 the lock casing;

Figure 2 is an edge elevational view of the lock showing the slotted openings in the side wall through which the tumbler handles extend;

Figure 3 shows perspective views of the 40 several parts of the combination lock mechanism;

Figure 4 is a plan view of the lock casing with the cover removed and showing the shackle in locked position;

Figure 5 is a cross-sectional view taken on line 5—5 of Figure 4;

Figure 6 is a plan view of the lock casing with the shackle in released position; and

Figure 7 is a cross-sectional view taken on line 7—7 of Figure 6.

While the lock casing may be constructed of any preferred design or configuration, the

same is herein illustrated as comprising a circular casing having a bottom wall 1, an 55 annular wall 2, and a top wall 3, the top wall 3 being retained in position on the lock casing by the center bolt 4. The annular side wall 2 of the lock casing is provided with a pair of slotted openings 5 and 6 through 60 which operating handles extend as shown in Figure 2 and said annular wall is further provided with openings for the passage of the short and long legs 7 and 8 respectively 65 of the shackle 9, the leg 8 of the shackle having a notch 10 formed in one side to receive the locking bolt or pin of the combination lock mechanism.

The detail parts of the lock mechanism are shown relatively positioned in Figure 3, while 70 the assembled formation thereof is illustrated in Figures 4 to 7. The combination lock mechanism comprises a sliding tumbler plate 11 of the form best illustrated in Figure 3 having a slotted opening 12 therein adjacent 75 one end through which the bolt 4 extends, the opposite ends of the sliding tumbler plate 11 having an end opening slot 13 that straddles the headed retaining pin 14 as shown in Figure 7, this end of the plate 11 being slidable 80 beneath the block 15 projecting inwardly from the adjacent portion of the annular side wall 2 of the lock casing and with which block the leg 8 of the shackle is engageable. A perpendicular pin 16 carried by the tumbler plate 11 is adapted to be received in the recess 10 in the shackle leg 8 and also in the vertical slot 17 in the inner end of the block 15 for locking the shackle in the casing as 85 shown in Figure 4. A notch 18 is formed in one side edge of the tumbler plate 11 to receive one end of the leaf spring 19 that has its outer end secured as at 20 to the inner face of the annular wall 2 as shown in Figure 6, the spring 19 tending to move the tumbler plate 11 and pin 16 carried thereby away 90 from the block 15 and shackle leg 8 to its releasing position. The opposite side edge of the tumbler plate 11 carries a perpendicular finger 21 that is adapted to be engaged by a 95 disk tumbler lug.

A disk tumbler 22 has a central opening 23 received on the bolt 4 and has a peripheral notch 24 of a size to receive the pin 16. An arm 25 projects from the peripheral edge of 100 the disk tumbler 22 with the outer end there-

of bent upwardly to form a tumbler lug 26. The tumbler disk 27 has an opening 28 received on the bolt 4 and is engaged with the tumbler disk 22, one side 29 of the tumbler disk 27 being cut away or reduced to provide a clearance for retracting movement of the pin 16 so that the disk 27 may rotate upon the bolt 4 when the pin 16 is received in the side notch 24 of the tumbler disk 22. A tumbler arm 30 projects from one side of the tumbler disk 27 while an oppositely disposed arm 31 that projects from the other side has the outer end thereof bent upwardly to form a tumbler lug 32. A handle 33 carried by the peripheral edge of the tumbler disk 27 extends through the slotted opening 5 in the side wall of the lock casing with a block 34 on the end thereof exteriorly of the lock casing to facilitate operation thereof.

20 A disk tumbler 35 with the central opening 36 is then placed on the bolt 4 and has a peripheral notch 37 to receive the pin 16, the disk 35 also carrying a relatively short arm 37 projecting from the peripheral edge thereof with the outer end bent downwardly to form a tumbler lug 38. The disk tumbler 39 having the central opening 40 is then placed on the bolt 4 and is likewise provided with a peripheral notch 41 and a relatively long arm 42 having the outer end bent upwardly to form a tumbler lug 43. A leaf spring 44 is secured intermediate its ends to the inner face of the annular side wall 2 of the lock casing and has one projecting end 45 thereof engaged by the lug 43 when in the position shown in Figure 6 for holding the disk tumbler 39 in its shifted position. The disk tumbler 46 having the central opening 47 then is placed on the bolt 4 and has a peripheral notch 48 and operating handle 49 that extends through the slotted opening 6 in the casing with an operating block 50 upon its outer end. A disk tumbler 51 having the central opening 52 is then placed on the bolt 4 and is provided with a side notch 53 and relatively long arm 54 bent downwardly at its outer end to form a tumbler lug 55 that is engageable with the other end 56 of the spring 44 to be held in its adjusted position. The top tumbler disk 57 having the central opening 58 is then placed on the bolt 4 and is provided with a peripheral notch 59 and a pair of depending tumbler lugs 60 and 61.

When the shackle leg 8 is locked within 55 the casing, the tumbler plate 11 is under tension of the spring 19 with the pin 16 extending into the leg opening 10 of the shackle and also into the vertical recess 17 of the block 15 so that the shackle is restrained from 60 movement, and in this position, the several tumbler disks illustrated in Figure 3, have plain edges thereof abutting the adjacent side of the pin 16 to hold the pin in its shackle-engaging position and against movement by 65 the spring 19. To release the pin 16 from

the shackle leg, it is necessary to align all of the peripheral notches in the tumbler disks therewith and to accomplish this object, the handle 33 is first moved from the lower end of the slot 5 to the upper end thereof. During 70 such movement, the handle 33 engages the tumbler lug 26 upon the disk tumbler 22 while the arm 30 upon the disk tumbler 27 engages the depending tumbler lug 38 upon the disk tumbler 35 for positioning the notch 24 in 75 the tumbler 22 and notch 37 in the tumbler 35 in alignment with the pin 16. The disk tumbler 46 is then operated by the handle 49, the handle engaging the tumbler lug 43 to move the notch 41 in the disk tumbler 39 into 80 alignment with the pin 16 with the tumbler lug 43 engaged with the spring 44 to be so held. The handle 49 also engages the lug 61 upon the tumbler disk 57 to move the same 85 therewith. The handle 49 is then moved toward the bottom end of the slot 6 and during such movement, the lug 55 upon the tumbler disk 51 is engaged thereby while the arm 54 upon the tumbler disk 51 engages the tumbler lug 60 upon the tumbler disk 57 for positioning the two notches 53 and 59 of the tumbler disks 51 and 57 respectively in alignment 90 with the pin 16. The tumbler lug 55 is also engaged with the spring 44 for holding the same in adjusted position. The handle 49 is then moved upwardly in the slot 6 as far as the indicator 62 as shown in Figure 2 to 95 position the notch 48 in the tumbler disk 46 carrying said handle into alignment with the pin 16. At this moment, all of the disk notches are aligned with the locking pin 16 and the tumbler lug 32 upon the tumbler disk 27 that has the handle 33 at the upper end of the slot 5 is engaged with the finger 21 upon the tumbler plate 11 and the spring 19 exerting its force moves the tumbler plate 11 and automatically shifts the handle 33 to the middle of the slotted opening 5, while the pin 16 moves into the aligned disk recesses. The shackle leg 8 is then released and the shackle 110 leg 7 may be moved outwardly of the lock casing while sliding movement of the leg 8 is limited by the pin 63 carried thereby and intended for engagement with an adjacent disk tumbler in its path of movement. The 115 shackle is placed in a locked position by first raising the handle 33 in the slot 5 and during such movement, the arm 31 upon the disk tumbler 27 engages the finger 21 on the tumbler plate 11 to move the pin 16 into the bolt 120 notch and block slot and subsequent operation of the handle 49 and lever 43 will displace the several disk tumbler notches from alignment with the locking pin 16.

From the above detailed description of the 125 invention, it is believed that the construction and operation will at once be understood, and while there is herein shown and described the preferred embodiment of the invention, it is nevertheless to be understood that minor 130

changes may be made therein without departing from the spirit and scope of the invention as claimed.

What I claim as new is:—

5. 1. In a combination padlock of the character described, a lock casing having openings therein for the legs of a shackle, a shackle having its legs extending into the casing openings, a plurality of disk tumblers 65 rotatable in the casing, a slidable locking pin interposed between the tumblers and one of the shackle legs to be engaged with either the shackle leg or tumblers for holding the shackle in either locked or released position, 10 tumbler lugs projecting from the peripheral edges of all but one of the disk tumblers and an operating handle carried by two of the disk tumblers extending through slotted openings in the casing.
20. 2. In a combination padlock of the character described, a lock casing having openings therein for the legs of a shackle, a shackle having its legs extending into the casing openings, a plurality of disk tumblers rotatable in the casing, a slidable locking pin interposed between the tumblers and one of the shackle legs, the shackle leg and tumblers being notched to selectively receive the pin and one of said tumblers being operated to move 25 the pin into the shackle leg notch, tumbler lugs projecting from the peripheral edges of all but one of the disk tumblers and an operating handle carried by two of the disk tumblers extending through slotted openings in 30 the casing.
35. 3. In a combination padlock of the character described, a lock casing having openings therein for the legs of a shackle, a shackle having its legs extending into the casing 40 openings, a plurality of disk tumblers rotatable in the casing, a slidable locking pin interposed between the tumblers and one of the shackle legs, the shackle leg and tumblers being notched to selectively receive the pin and one of said tumblers being operated to move 45 the pin into the shackle leg notch, a sliding tumbler plate carrying the pin, a spring for normally moving the plate and pin away from the shackle leg, tumbler lugs projecting from the peripheral edges of all but one of the disk tumblers, an operating handle carried by 50 two of the disk tumblers extending through slotted openings in the casing, and a spring device for holding a pair of the tumbler disks in releasing position.
55. 4. In a combination padlock of the character described, a lock casing having openings therein for the legs of a shackle, a shackle having its legs extending into the casing 55 openings, a plurality of disk tumblers rotatable in the casing, a slidable locking pin interposed between the tumblers and one of the shackle legs, interengaged lugs carried by the peripheral edges of some of said tumbler disks, operating handles carried by two tumbler disks, said disks and shackle leg being 60 notched to selectively receive the locking pin, and a spring device for holding a pair of the tumbler disks in releasing position.
60. 5. In a combination padlock of the character described, a lock casing having openings therein for the legs of a shackle, a shackle having its legs extending into the casing 65 openings, a plurality of disk tumblers rotatable in the casing, a slidable locking pin interposed between the tumblers and one of the shackle legs, the shackle leg and tumblers being notched to selectively receive the pin and one of said tumblers being operated to move the pin into the shackle leg notch, tumbler lugs projecting from the peripheral edges of all but one of the disk tumblers, an operating handle carried by two of the disk tumblers extending through slotted openings in the casing, and a spring device for holding a pair of the tumbler disks in releasing position.
7. In a combination padlock of the character described, a lock casing having openings therein for the legs of a shackle, a shackle having its legs extending into the casing 80 openings, a plurality of disk tumblers rotatable in the casing, a slidable locking pin interposed between the tumblers and one of the shackle legs, the shackle leg and tumblers being notched to selectively receive the pin and one of said tumblers being operated to move the pin into the shackle leg notch; a sliding 85 tumbler plate carrying the pin, a spring for normally moving the plate and pin away from the shackle leg, tumbler lugs projecting from the peripheral edges of all but one of the disk tumblers, an operating handle carried by 90 two of the disk tumblers extending through slotted openings in the casing, and a spring device for holding a pair of the tumbler disks in releasing position.
10. In a combination padlock of the character described, a lock casing having openings therein for the legs of a shackle, a shackle having its legs extending into the casing 95 openings, a plurality of disk tumblers rotatable in the casing, a slidable locking pin interposed between the tumblers and one of the shackle legs, interengaged lugs carried by the peripheral edges of some of said tumbler disks, operating handles carried by two tumbler disks, said disks and shackle leg being 100 notched to selectively receive the locking pin, and a spring device for holding a pair of the tumbler disks in releasing position.

In testimony whereof I affix my signature.

JOHN POTURNAJ.
